(57) **CLAIM**

The ornamental design for a container for high pressure gas,
as shown and described.

DESCRIPTION

1. Container for high pressure gas

1.1 : Perspective

1.2 : Front

1.3 : Enlarged view at right end

1.4 : Right

1.5 : Top

The rear view is a mirror image of the front view shown in
Fig. 1.2 , and the bottom view is identical to the top view
shown in Fig. 1.5 . The broken lines represent portions of the
container for high pressure gas which form no part of the
claimed design. The dot-dash style broken lines represent
the boundary between claimed and unclaimed portions of
the design and forms no part of the claim.
